UNITED STATES PATENT OFFICE.

THOMAS M. MOORE, OF NEW YORK, N. Y.

DESIGN FOR A CIGAR-TRAY.

49,071.

Specification for Design.

Patented May 16, 1916.

Application filed December 10, 1915. Serial No. 66,210. Term of patent 3½ years.

To all whom it may concern:

Be it known that I, THOMAS M. MOORE, residing at Manhattan, in the county of New York and State of New York, have invented a certain new, original, and ornamental Design for a Cigar-Tray, of which the following is a specification, reference being had to the accompanying drawing, forming part thereof.

Copies of this patent may be obtained for five cents each, by addressing the "Commissioner of Patents, Washington, D. C."

I claim:

The ornamental design for cigar tray as shown.

THOMAS M. MOORE.
